STEAM SUPERHEATER AND METHOD OF
CONTROLLING SUPERHEAT

Frederick W. Linaker, Forest Hills, N. Y.

Application March 7, 1944, Serial No. 525,334

6 Claims. (Cl. 122—479)

1

This invention relates to steam superheaters, and also to methods of controlling the temperature of the superheated steam, and provides improvements therein.

In a boiler combination comprising steam-generating elements and steam superheating elements, the present invention provides a novel combination and arrangement by which improved results are obtained. The invention provides improved results in the control of the temperature of the superheated steam delivered by the superheater and in the protection of the superheater element from over-heating. It provides for delivery of superheated steam at approximately a desired predetermined temperature, under variations of steam delivery and fuel consumption.

The invention may be applied to boiler combinations in which the heating of the superheater element is done by convection, by radiation, or by a combination of convection and radiant heat.

Several embodiments of the invention are illustrated in the accompanying drawings. The drawings also illustrate several forms of apparatus in which the method of the invention may be carried out. The apparatus invention, however, may receive other embodiments than those herein specifically illustrated and described.

In said drawings—

Figs. 1—5 illustrate one embodiment;

Fig. 1 being a vertical sectional view through a steam boiler, showing so much thereof for those skilled in the art as is necessary to illustrate the invention;

Fig. 2 is a plan view looking down on the superheater elements, headers and distributor seen at the upper right-hand part of Fig. 1;

Fig. 3 is a vertical sectional view through the distributor;

Fig. 4 is a front elevation of a distributor; and

Fig. 5 is a view in side elevation of a distributor.

Fig. 6 illustrates another embodiment of the invention, which includes a pre-superheater, shown at the left side of the figure;

Figs. 7, 8 and 9 are views illustrating a different embodiment of distributor from that illustrated in Figs. 3, 4 and 5;

Fig. 7 being a vertical sectional view;

Fig. 8 a front elevation; and

Fig. 9 being a view in side elevation, with the pipes shown in the other figures omitted.

Fig. 10 is a view similar to Fig. 2 illustrating an embodiment comprising a plurality of distributors (35, 35A).

2

Referring to said drawings, numeral 1 designates the outer walls of a steam boiler or generator (only part of the walls being shown). The boiler is fired by any suitable means (not shown). A boiler of the water-tube type has been shown by way of illustration. The tubes may have any suitable or known arrangement. Suitable baffles for controlling the flow of the combustion gases with relation to the tubes may be provided. Vertical baffles 3 and 4 and transverse baffles 5 are illustrated.

Sets of vertical water-tubes 8 and 9 are illustrated, connected at the lower ends thereof to a water-drum 10 and at the upper ends thereof to a steam-drum 12. Other sets of water-tubes, such as 7, connected with water-drum 10 and steam-drum 18, are provided, according to the design of the boiler. The sets of water-tubes 7 are connected at the lower ends thereof to water-drum 10 and at the upper ends thereof to steam-drum 18. Steam from drum 12 flows to drum 18 through a pipe or pipes 19. Other sets of water-tubes 14 and 16 in another part of the boiler are shown.

Numeral 25 designates the superheater part, which is in the form of a set of superheater tubes or elements. These tubes or elements are usually, and as here shown, coiled. Some of the superheater tubes or elements 25 are divided into serial sections, here shown as two, a section 27 and a section 29. The superheater tubes or elements which are not divided into sections are connected at one end to an inlet-header or receiver 31, and at the other end thereof to an outlet-header or receiver 33. The tubes of section 27 are connected at one end to the inlet-header 31 and at the other end to a distributor 35, and the tubes of section 29 are connected at one end to the distributor 35 and at the other end to the outlet-header 33. A plurality of these distributors 35, 35A may be provided, if desired, and as illustrated in Fig. 10, the distributors may be operated at different temperatures so that a full control of the temperature of the superheated steam at the outlet-header 33 may be obtained.

Steam lines 40 are provided from the steam-drum 18 to the superheater inlet header 31, and other steam lines 41 are provided from the drum 18 to the distributor 35.

The function of the distributor 35 is to control the flow of saturated steam, so that it flows serially through the two sections 27 and 29 of the superheater coils or elements 25 to the outlet-header 33, or in parallel to the outlet-header 33 through each section 27 and 29.

The distributor 35 may be any suitable valve-arrangement, but advantageously has the structure illustrated in Figs. 3 and 4, and comprises a chambered body 45 and headers or branches 47, 48, 49, 50 and 51. A ported partition 53 is provided between the branches 47 and 48; a ported partition 55 is provided between branches 50 and 51; a ported partition 57 is provided between branches 49 and 50, and a solid partition 59 is provided between branches 48 and 49.

The sections 27 and 29 of superheater tubes or elements 25 communicate respectively with branches 50 and 51 of distributor 35. Pipes 56 connect branches 47 and 51 of the distributor. Pipes 58 lead from branch 49 to the superheated steam outlet-header 33.

A multiple valve 60, comprising valves 62 and 63, is provided for controlling the ports 53, 55 and 57 of the partitions. A motor for operating the valve 60 may be and as here shown, is incorporated in the distributor. To this end, the multiple-valve 60 is provided with a piston 66 and a cylinder 67 is provided between the partition 59 and another partition 68 in the chamfered body 45. Steam or other suitable fluid for operating piston 66 is admitted to and vented from cylinder 67 through pipes 70 and 71, and 72 and 73.

The operation of the multiple-valve 60 of distributor 35 may be manual, but is advantageously done by automatic devices, as illustrated. Referring to Fig. 5, fluid for actuating piston 66 of distributor 35 is admitted to and vented from cylinder 67 through two electrically operated or fluid operated valves of well-known types, such as Brown Instrument Co. diaphragm valves 71 and 78, and a thermostat 80 in the superheater outlet-header 33, acting through any well-known electrical arrangement (not shown), energizes the electrical valves to effect the operation of the distributor 35. The valves 71 and 78 are two-way valves. Fluid enters valve 71 through a pipe 82 and flows to one side or the other of piston 66 through pipes 70 and 72 in accordance with the position of the valve. Fluid is vented from one side or the other of piston 66 through pipes 71 and 73, valve 78, and a vent-pipe 84 in accordance with the position of valve 78. When valve 71 admits fluid to one side of piston 66, valve 78 operates to close the vent from that side and open the vent from the opposite side and vice versa.

Operation

A temperature desired for the superheated steam is determined, and, when automatic means for operating distributor 35 is provided, the thermostat 80 is set at a temperature slightly above the predetermined temperature.

When the superheated steam in outlet-header 33 is at or below the predetermined temperature, the automatic valves 71 and 78 act to put or keep the multiple-valve 60 of distributor 35 in a position in which steam flows serially through the sections 27 and 29 of the superheater tubes or elements (position shown in Fig. 3). Saturated steam from drum 18 enters superheater inlet-header 31 through pipes 40, then through superheater tube section 27 to branch or part 50 of distributor 35, then into branch 51 through the port in partition 55 and into and through the superheater tube section 29 to superheater outlet-header 33. Those of the superheater tubes or elements 25 which are not connected with a distributor, conduct steam directly from intake-header 31 to outlet-header 33. The number of the superheater tubes or elements which are con-

nected to a distributor is governed by engineering design for effecting the desired superheat control for the installation to which the invention is applied.

When the superheated steam in outlet-header 33 rises above the predetermined temperature, the thermostat 80 actuates the valves 71 and 78 to operate the multiple-valve 60 of the distributor 35 so as to position it to control the flow of saturated steam in parallel through the superheater sections 27 and 29, and thereby receive less superheat. The action of the thermostat 80 is to energize valves 71 and 78 so that valve 71 opens pipe 70 to admit fluid to the upper side of piston 60 (and also closes pipe 72), and valve 78 opens pipe 73 leading to vent pipe 84 and closes pipe 71. Piston 60 is moved downward with reference to its position shown in Fig. 3, opening the ports in partitions 53 and 57 and closing the port in partition 55.

Saturated steam flows to superheater section 27 and thence to outlet-header 33, from drum 18 through pipes 40, intake-header 31, superheater tube section 27, branch or part 50 of distributor 35, then to branch 49 through the port in partition 57, and then to the superheater outlet-header 33 through pipes 58. Saturated steam also flows to superheater section 29, and thence to outlet-header 33, from drum 18, through pipes 41, branch or part 48 of distributor 35, then into branch 47 through the port in partition 53, then through pipes 56 into branch or part 51, and then through the superheater tube section 29 to the outlet-header 33.

When the temperature of the superheated steam in outlet-header 33 falls below the predetermined temperature, distributor 35 is again actuated to control the flow of steam through the superheater tube sections 27 and 29 so that the flow is serial. By a succession of operations of distributor 35 to cause serial flow or multiple flow through the superheater tube sections 27 and 29 a predetermined temperature for the superheated steam at the outlet-header 33 is very closely approximated.

In Fig. 6 there is illustrated an embodiment which is advantageous where the volume or temperature of the products of combustion passing over the superheater elements is, at times, not sufficient to raise the temperature of the superheated steam to the final degree desired. The embodiment includes a pre-superheater section 90 (in the form of tubes or elements) in a part of the boiler where the temperature is comparatively low. Much of the structure of this embodiment is similar to that of Fig. 1, and similar parts in the two views are designated by the same reference numerals, and the description thereof is not repeated.

Numeral 93 designates a distributor or means for controlling the flow of saturated steam from drum 18 to the inlet-header 31 of the superheater, either directly, or through the pre-superheater section 90. The distributor 93 may be any suitable valve arrangement, but advantageously, as shown in the drawings, comprises a chambered body 95 having branches 97, 98, 99. Valves 101, 102 control the communication between the branches, as hereinafter described. The valves may be manually operated, or be operated through the action of the thermostat 80 and suitable known electrical means, as illustrated in the drawings.

Pipes 40 convey saturated steam from drum 18 to branch 98 of distributor 93. Pipes 105 con-

nect branch 97 with the superheater inlet-header 31. The intake ends of pre-superheater elements 98 are connected to branch 99 and the delivery ends to inlet-header 31.

When the temperature of the superheated steam in outlet-header 33 is below a predetermined or desired temperature, the distributor 93 operates (or is operated) to move valve 101 to close branch 97 from branch 98 and valve 102 to open branch 98 to branch 99. Saturated steam flows from drum 18 through pipes 48 to branch 98 of distributor 93, then to branch 99, then through the pre-superheater 98 to inlet-header 31. From the superheater inlet-header 31 the flow of steam is controlled by the distributor 35 in the manner heretofore described in connection with the embodiment of Fig. 1. When the temperature of the steam at outlet-header 33 is such as not to require the additional heat provided by the pre-superheater 98, the distributor 93 operates by the means previously described (or is operated), to close branch 99 of distributor 93 from branch 98 and open branch 97 to branch 98. Saturated steam then flows to inlet-header 31 by way of pipes 48, branches 98, 97 and pipes 105.

An embodiment of distributor 35 differing somewhat from that of Figs. 1 to 5 is illustrated in Fig. 6, and in greater detail in Figs. 7, 8 and 9. Parts in Figs. 6 to 9 similar to parts in Figs. 1 to 5 are designated by the same reference numerals, and the description thereof is not repeated. Referring to the Figs. 6 to 9, the valve operating motor is located outside of the chambered body 45 and the provisions constituting the cylinder portion 67 are omitted. In place of disk-type valves, butterfly type valves 110, 111, and 112 are provided, which have stems 115, 116, 117 projecting through the chambered body 45. The valves 110, 111, 112 are operated in any suitable manner; in the illustrated means, the stems have arms 120, 121, 122 thereon which are connected to a drag-link 125 through which they act in unison. A suitable motor, as an electromagnetic motor 127, or a power cylinder of the well-known Brown Instrument Co. type is provided for operating the valves through the drag-link 125. This operation of the motor 127 is under the control of thermostat 80 through suitable electrical connections, as previously stated in reference to Fig. 1.

Modes of procedure in carrying out the method of this invention are apparent from the foregoing description. Briefly stated, saturated steam is superheated in superheater elements, some of which are arranged to operate in series and others of which are arranged to operate either in series or in parallel. When the temperature of the superheated steam in the receiver or outlet-header becomes too high, the superheat elements, which are arranged to operate either in series or in parallel, are caused to operate in parallel and thereby reduce the temperature of the superheated steam in the receiver or outlet-header. When the temperature of the superheated steam in the receiver or outlet-header falls too low, the superheater elements which are arranged to operate either in series or in parallel are caused to operate in series, and hotter steam is delivered to the receiver or outlet-header, thereby raising the temperature of the steam. Control of the temperature of the superheated steam in the receiver or outlet-header is effected by operating certain of the superheater elements either in series or in parallel, alternately. This may be

effected by controlling the steam-flow through the distributors either by manually controlled valves, or through automatic means.

What is claimed is:

1. A steam superheater comprising a steam intake and a receiver for superheated steam, a set of elements in which steam is superheated always in serial arrangement between said intake and said receiver, another set of superheater elements in which steam may pass either serially or in parallel from said intake to said receiver, a distributor interposed in said second set of elements having means for compelling the steam to flow in said second set of elements from said intake to said receiver either serially or in parallel, said means comprising a thermostat at the receiver for superheated steam and motor operated valves operated therefrom opening and closing chambers in said distributor connecting said second set of elements for said operation in series only, when the superheated steam delivered to said receiver does not exceed a predetermined temperature, and opening and closing chambers in said distributor connecting said second set of elements for said operation in parallel when the temperature of the superheated steam in said receiver exceeds the predetermined temperature to deliver superheated steam to said receiver at a temperature below said predetermined temperature, thereby to control the temperature of the superheated steam in said receiver approximately to said predetermined temperature.

2. A steam superheater, according to claim 1, further comprising a second distributor and associated superheater elements, motor operated valves and thermostat, and wherein said thermostat associated with said second distributor is set at a temperature different from the temperature at which the thermostat associated with the first distributor is set to act to control more closely the temperature of the superheated steam in the receiver.

3. A steam superheater comprising a steam intake and a receiver for superheated steam, a set of elements in which steam is superheated always in serial arrangement between said intake and said receiver, another set of superheater elements in which steam may pass either serially or in parallel from said intake to said receiver, a distributor with which said second set of superheater elements is connected intermediate of said elements, a duct for conveying saturated steam directly to said distributor, a duct for conveying superheated steam directly from said distributor to said receiver, and means for actuating said distributor to connect the elements of said second set of superheater elements which are connected thereto for said serial operation, when the superheated steam in said receiver does not exceed a predetermined temperature, and when the superheated steam in said receiver is above said predetermined temperature, to connect the part of the said second set of superheater elements which is before the distributor with said duct for conveying superheated steam directly to the receiver, and the part of the second set of superheater elements which is after the distributor with said duct for conveying saturated steam directly to the distributor and thence to the receiver, thereby to control the temperature of the superheated steam in said receiver approximately to said predetermined temperature.

4. A steam superheater according to claim 1, wherein said distributor comprises ported chambers A, B, C, D, E; A being a chamber in com-

munication with chamber E and with chamber B through its port; B being a chamber in communication with a supply of saturated steam; C being a chamber in communication with the superheated steam receiver and with chamber D; D being a chamber in communication with chambers C and E through the ports thereof, and with the delivery end of the part of said second set of superheater elements which is before the distributor; and E being a chamber in communication with chamber D through its port and with the intake end of the section of said second set of superheater elements which is after the distributor; a duct conducting saturated steam to said chamber B, a duct connecting chambers A and E, and a duct from chamber C to the superheated steam receiver; and valves for closing the ports between chambers A and B, and C and D, and opening the port between chambers D and E for said serial connection of said second set of superheater elements to said superheated steam receiver, and, for parallel connection between said second set of superheater elements and said superheated steam receiver, closing the port between chambers D and E and opening the ports between chambers A and B and C and D.

5. A steam superheater according to claim 1, wherein said valves are in the form of a multiple valve, and further comprising a motor for moving said multiple valve to its positions for serial and parallel flow respectively.

6. A method of controlling the temperature of superheated steam delivered from steam superheaters comprising conducting saturated steam in series through superheater elements arranged only for series flow and concurrently conducting

saturated steam in series through other superheater elements, arranged for either series or parallel flow, while the delivered superheated steam has a temperature which does not exceed a predetermined temperature, and upon said delivered superheated steam exceeding said predetermined temperature, conducting saturated steam in parallel through said superheater elements arranged for either series or parallel flow, concurrently with conducting saturated steam in series through those of the superheater elements arranged always for series flow, to maintain approximately a predetermined temperature of the delivered superheated steam.
